UNITED STATES PATENT OFFICE.

JAMES C. POTTER, OF PAWTUCKET, RHODE ISLAND.

EVENING MECHANISM FOR COTTON-OPENERS, &c.

SPECIFICATION forming part of Letters Patent No. 399,076, dated March 5, 1889.

Application filed July 9, 1888. Serial No. 279,395. (No model.)

To all whom it may concern:

Be it known that I, JAMES C. POTTER, of Pawtucket, in the State of Rhode Island, have invented a certain new and useful Improvement 5 in Evening Mechanism for Cotton-Openers and other Engines or Machines for Working Cotton and other Fibrous Materials, of which the following is a specification.

My invention has relation more particularly to the scale-levers which are generally used in evener mechanism for the purpose of transmitting the movement of the evener-plates or other evener devices over or under which the fibrous material passes on its way 15 through the machine to the belt of the cone-drums.

Heretofore, so far as I am informed, the levers which compose the scale-lever system have been fulcrumed one upon the other by 20 knife-edges, those levers which are above or nearer to the evener-plates resting upon and bearing with their knife-edges against the levers below or farther removed, all the levers which compose the system being carried 25 by a single lever, known as the "main scale-lever." This arrangement involves a somewhat expensive construction, and is objectionable besides on various accounts. The expense is principally due to the fact that 30 after the levers are cast their fulcrum-points must be ground to furnish the necessary knife-edge. Owing to the manner in which they are arranged and fitted together they have no positive connection with one another, 35 and thus require extraneous lateral support of some kind to hold them in the same plane, and to prevent lateral wabbling of the system. This is equally true whether the system is arranged in a vertical or in a horizontal 40 plane. The contact between the scale-lever system and the lateral supporting devices therefor engenders friction, which interferes at times with the easy movement of the levers, while the lateral supporting devices 45 cover up the levers to a certain extent and prevent them from being readily got at and cleansed or brushed, as they must be in order to prevent them from becoming clogged or impeded by lint, dust, and the like. All of 50 these objections, as well as others which might be noted, are removed by my invention.

The characteristic of my improvement is that the levers which compose the scale-lever system are suspended from above, instead of being supported from beneath, as has heretofore been customary. By this arrangement I am enabled to do away with knife-edges, so that all grinding can be dispensed with, all that is needed in order to finish the castings 55 being to tumble them in a tumbler or "rattler," as it is sometimes called; and, as the scale-lever system is suspended, it will hang in a vertical or substantially vertical plane without the aid of any lateral supports. The 60 labor of fitting together the parts of the system is materially reduced, there is less liability of its getting out of order, and it is equally as sensitive and quick to respond to the slightest movement of the evener-plates as 65 any of the most approved scale-lever systems heretofore in use.

In the accompanying drawings, Figure 1 is a side elevation of so much of a cotton-opener as needed to illustrate my invention, portions of 70 the frame being broken away in order to more clearly expose to view the working parts. Fig. 2 is a sectional view, partly in elevation, of the feed and evener rolls, plates, and levers, together with some parts of the machine immediately adjacent thereto. Fig. 3 is a front elevation of the scale-lever system in connection with the mechanism which I on the whole prefer for transmitting the movement of the system to the cone-drum belt-shifter. 85

A is the frame of the machine.

B is a combined evener and feed-roll supported in fixed bearings.

C is a feed-roll which co-operates with roll B for feeding purposes, and is held up against 90 the same with yielding pressure by pivoted weighted levers *a*, which, through the sliding pins *b*, bear upward against the vertically-movable journal-boxes *c* of the roll C.

D are evener-plates, which co-operate with 95 roll B for evening purposes. This combination of evener-plates and a feed-roll with a combined evener and feed-roll is not here claimed by me, but is the subject of my application for Letters Patent, Serial No. 266,512, filed March 8, 1888. So far as my present improvement is concerned I, of course, am not limited to this particular combination. Any other construction and arrangement of the 100

evener devices between which the cotton passes on its way to the beater can be availed of without affecting my invention.

5 E is the knife-edge bar on which the evener-plates are fulcrumed.

F is the feed-trough, and G is the feed-apron.

With a view to readily adjust the knife-edge bar I prefer to secure its ends in brackets 10 H, which are mounted and swivel on the ends of the axle d of the front roller of the feed-apron. The bracket can be secured in adjusted position by a set or clamping screw, e, which passes through two slots, f, the one in 15 the bracket and the other in the side of the feed-trough, which cross one another at right angles.

The arms or extensions B' of the evener-plates which connect with the scale-lever system can be attached to the plates either side of their fulcrum. I prefer, however, that these arms should start from the plates at a point in front of the fulcrum, passing down below the knife-edge bar, and thence extending horizontally out beyond the front wall, A', of the frame of the machine, as shown. By this arrangement I gain in compactness without detracting from efficiency, and, what is even more material, I am enabled to insert 20 and remove the plates and their arms with great ease and without disturbing other parts of the machine. The tail g of each evener-plate back of the fulcrum is short, and is so shaped that it will bring up against the knife-edge bar when the plate itself is adjusted, so 25 that it is in contact with the roll B.

The number of evener-plates used can of course vary. In the machine illustrated in the drawings there are supposed to be sixteen 30 plates, or, rather, eight pairs of plates. The arms D' of each pair of plates are connected to opposite ends of the small scale-levers I of the top row of the scale-lever system by links h, each of which hooks over its arm D' and 35 under that arm or end of the lever I to which it is to be connected. Levers I are by similar hooks, h', connected in pairs to the ends of the larger scale-levers, I', of the next row, and so on to the still larger levers, I'', and the 40 main scale-lever I''. Each lever is formed at its ends with rounded recesses or hook-like portions, under which the ends of the connecting-links from above catch, and at its center with a like recess, over which the link 45 from below catches. All of the levers can be readily cast in this shape, and when once cast require no other finishing than that hereinbefore mentioned. The connecting-hooks also 50 can be readily and cheaply made, so that the expense of the system as a whole is but comparatively little. Manifestly, the parts can 55 be more easily fitted together, and when once connected cannot well get out of order or adjustment. The scale-lever system hangs down 60 under the feed-trough and outside of the front wall, A', of the frame of the machine. It is 65 therefore out of the way in a position where

it is shielded to great extent from dust and lint, but where at the same time it is entirely open to access, so that the workman can readily get at it to brush or dust it from time to time.

The main scale-lever can impart its movement to the cone-belt shipper through the intermediary of any suitable instrumentalities, 70 of which a large variety are now in use. The particular mechanism shown by me in the drawings is, however, that which I prefer.

From an eye, i, at the center of the main scale-lever is suspended by a hook a bracket, 80 J, which supports the lever K, fulcrumed at j to the front wall of the frame by a stud, k, which passes through a longitudinal slot, l, in the lever. The lever preferably rests upon the end of a set-screw, m, with which the 85 bracket is provided, the end of said screw being pointed and entering a plain but similarly-pointed socket in the under side of the lever. By means of this screw the initial adjustment of the lever (and consequently of 90 the cone-belt) can be effected. A check-nut, m', holds the set-screw in its adjusted position. A weight, n, on the lever holds it down. The free end of the lever is forked and straddles the end of an arm, o, fixed on a shaft, o', 95 journaled in the cone-drum box A'' and having fixed to it at an appropriate point a shorter arm, p, which, by a link, r, is connected to the crank-arm of one of the pivoted belt-shippers L, these shippers being geared together 100 as usual at their abutting ends, so as to move in unison.

M N are the upper and lower cone-drums. The belt connecting them is omitted to avoid confusing the parts.

105

It will be noted that the cone-drum box extends up alongside of that portion of the frame of the machine where one of the end brackets for supporting the knife-edge bar is located. In practice, however, there is a space 110 of some six inches between these parts, leaving ample room for the workman to get at the bracket.

Having described my improvement and the best way now known to me of carrying the 115 same into effect, what I claim herein as new and of my own invention is as follows:

1. A scale-lever system comprising scale-levers having connecting-links, whereby the levers below are suspended from those next 120 above, in combination with evener-arms and links whereby the topmost scale-levers are connected to and suspended from said arms, substantially as and for the purposes hereinbefore set forth.

2. In combination with the evener-arms, the scale-lever system comprising scale-levers and connecting-links, whereby the levers below are suspended from those next above and the topmost scale-levers are connected to and 130 suspended from said arms, said scale-lever system being located outside of the front wall of the machine and under the feed-trough, substantially as set forth.

125

130

3. The combination of the evener-plates, the knife-edge bar, its swiveled adjustable supporting-brackets, and means for securing said brackets in adjusted position, substantially as and for the purposes hereinbefore set forth.

4. The combination of the evener-plates and arms, the suspended scale-lever system connected to said arms and having the scale-levers below suspended from those next above, the cone-drums, cone-drum belt, and belt-

shipper, and belt-shipper-actuating mechanism connected to and operated by the main-scale lever, all substantially as and for the purposes hereinbefore set forth.

In testimony whereof I have hereunto set my hand this 3d day of July, A. D. 1888.

JAMES C. POTTER.
